UNITED STATES PATENT OFFICE.

HENRY L. FERRIS, OF HARVARD, ILLINOIS.

DESIGN FOR A TANK HEATING-STOVE.

SPECIFICATION forming part of Design No. 23,811, dated November 13, 1894.

Application filed June 21, 1894. Serial No 515,312. Term of patent 7 years.

To all whom it may concern:

Be it known that I, HENRY L. FERRIS, a citizen of the United States of America, residing at Harvard, in the county of McHenry and State of Illinois, have invented a new and original Design for Tank Heating-Stoves, of which the following is a specification.

My invention relates to a certain new and original design for tank heating stoves illustrated in the accompanying drawing, in which is shown a lateral perspective of the same.

Looking at the drawing, my design will be seen to have a comparatively large cylindrical horizontal body, A, extended at one end into a portion, B, of substantially the same size, but rising at an oblique angle to the main portion of the body. At the other end the

body has a horizontal extension of reduced size terminating in a substantially vertical portion also of reduced size.

The essential portion of my invention I consider the shape of the body, A, B, one portion of the same being substantially horizontal and the other rising therefrom at an oblique angle thereto.

I claim as new and desire to secure by Letters Patent—

The design for a tank heating stove herein shown and described.

HENRY L. FERRIS.
